DISPLAY CABINET

**Edvin F. Bjoro and John M. Fisher, Huntington,
N. Y., assignors to The Spool Cotton Company,
Newark, N. J., a corporation of New Jersey**

Application November 6, 1945, Serial No. 626,938

1 Claim. (Cl. 312—290)

1

This invention relates to a display cabinet for relatively small articles of merchandise designed to be used where the customers cannot only see the merchandise but actually take it from the cabinet or receive it from a sales person stationed near the cabinet. An object of the invention is to produce a cabinet of this general type equipped with an upper portion designed to display the merchandise, a lower portion designed to store a supply of the merchandise and the whole device so constructed that it is sufficiently attractive so that it makes a fitting piece of furniture for the finest kind of a sales establishment.

The principles of the invention will be defined in the claim ultimately appended hereto. It will be illustrated with the following description taken in conjunction with the drawings, in which

Fig. 1 is a front view.

Fig. 2 is a side or end view.

Fig. 3 is a section through 3—3 of Fig. 1.

Fig. 4 is a section through 4—4 of Fig. 1.

Fig. 5 is a bottom plan view of a drawer.

Fig. 6 is a section through 6—6 of Fig. 5.

Fig. 7 is a section through 7—7 of Fig. 3.

Fig. 8 is a section through 8—8 of Fig. 4.

Fig. 9 is an enlarged view of the upper left hand corner of Fig. 3 showing some merchandise in place on the uppermost tray.

Fig. 10 is a section through 10—10 of Fig. 9.

Fig. 11 is a plan view of one of the spool trays shown in section in the upper part of Fig. 3.

Fig. 12 is a section through 12—12 of Fig. 4.

Fig. 13 is a fragmentary plan view of one of the trays seen in the upper part of Fig. 4, and

Fig. 14 is a perspective view of one of the partitions used in the upper display compartment shown in Fig. 4.

Looking at Fig. 1 the display cabinet may be considered as made up of four sections A, B, C and D. Section A consists of an end panel 1, a top 2, a front panel 3. On the inside thereof is a shelf 4. The top of this section may be used for display purposes or for wrapping articles of merchandise if that is desirable. It may also be used to support a cash register. The interior of this section can be used to store merchandise or stationery, paper, boxes or the like.

Section B has a base portion in which are disposed five drawers and a storage space. This section is made up of two end panels 5 and 6 tied together with horizontal frame members 7, 8 and 9. The five drawers are shown at 10, 11, 12, 13 and 14. The drawers are designed to slide on transverse tracks such as that shown at 15 in Fig. 3. All the drawers in the display cabinet run upon the same kind of tracks and are exactly

2

the same in construction so the same identifying numbers will be used in designating corresponding parts. Track 15 is also shown in Figs. 4, 5, 6, 7 and 8. Each of the tracks shown at 15, and there is one for each drawer in the cabinet, is equipped with a longitudinal pair of grooves shown at 16 and 17 running from one end of the track to the other. Each drawer is equipped with a cooperating track on the bottom thereof such as that shown at 20. This track 20 is grooved along the middle to receive the complementary track 15 therein. The drawers are designed to be withdrawn from either the front or the back of the cabinet and each end of each drawer is equipped with a handle 25. These handles are identical on each drawer so will be given a single numeral to designate all of them.

In order to prevent the drawers from being accidentally pulled all the way out from the cabinet suitable stop means is incorporated in the tracks. Each drawer is equipped with a pair of cylindrical plugs projecting downwardly from the bottom thereof, one near each end and one into each of the grooves 16 and 17. The plug which operates in groove 16 is shown in Fig. 5 at 26 and the plug intended to slide along groove 17 is shown at 27. There are removable stops or blocks insertable in the grooves 16 and 17 to block said grooves. One such stop is shown at 28 in Figs. 3, 4 and 7. The stop in question is made up of a disc-like member mounted on a short cylindrical body. A suitable hole is recessed in the track 15 in each one of the grooves 16 and 17. In groove 16 the recess for the stop 28 is near the front of the cabinet and the recess for stop 28' near the rear as shown in Fig. 3. The recess for the stop 29 in the groove 17 is near the rear of the cabinet and the recess for the stop 29' near the front as seen in Fig. 5. These stops are readily removable. When there is no stop in either groove 16 or 17 the drawer may be fully withdrawn from either the front or the back of the cabinet. If a stop is placed in groove 16, for instance, near the front of the cabinet and the plug 26 which slides along groove 16 is near the rear of the drawer as shown in Fig. 5, the drawer may be drawn out from the front of the cabinet until the plug 26 engages the stop 28 when it can be moved no further. Likewise if a stop 29 is in place in groove 17, for instance, near the rear of the cabinet, plug 27 will engage this stop when the drawer is withdrawn from the rear of the cabinet. By using these removable stops it is possible to arrange the operation of the drawers so that they may not be completely withdrawn from either the front or the back or it may be

arranged that they can be withdrawn from either the front or the back but not both and finally with no stops at all, the drawer can be completely withdrawn from either front or back.

The drawer portion of sections B and D are equipped with suitable braces underneath the center thereof as shown at 30 and 31 (Figs. 3 and 4). These braces are joined to the front piece 8 and the rear piece 8' by means of longitudinal strips 32 and 33. The juncture of the longitudinal pieces 8 and 8' with the strips 32 and 33 and the braces 30 and 31 makes a solid foundation for the cabinet.

On top of the drawer containing portion of section B is a display portion equipped with sliding trays as shown in Figs. 1 and 3. This upper portion is designated 40 and is divided into 3 identical compartments shown at 41, 42 and 43. Only one of these will be described because the other two are just like it. Each compartment consists of triangular shaped side or end pieces 45 and 46. A rear wall 41 is shown in Fig. 3, which wall is relatively high. The top and front of these display sections are open for the most part. However, near the rear of the top of this section is a display panel 50 mounted in suitable longitudinal pieces 51 and 52. The names of the articles on display or the name of the manufacturer thereof or any other suitable information may be placed on this panel.

The side walls of this display or trade section 41 are equipped with parallel tray supporting grooves. Those in panel 46 are best shown in Fig. 3, the uppermost one 53 is very short, the next one 54 is somewhat longer and the others 55, 56 and 57 are still longer and 57 the bottommost groove is the longest. There are a corresponding set of grooves in the panel 45 and each pair of corresponding grooves is designed to receive a display tray which trays are shown in Figs. 1 and 3. The uppermost one is shown at 60 and the next one underneath at 61 and so on 62 and 63 and the lowermost one 64. These trays are designed to slide in the grooves in the side panels like drawers and may be removed from the back of the display cabinet. Each tray is made up of a front section 65, a back section 66 and two sides 67 and 68 (see Figs. 9 and 11). All the trays are identical except that the uppermost one is the shortest and the lowermost one the longest. The details of construction of only one tray will be described. The front and back pieces 65 and 66 are equipped with mortised grooves to receive little tags or signs to indicate articles, prices, materials or other descriptive matter for the articles displayed in the tray.

The trays here shown are equipped to receive spools of thread but of course other articles may be displayed in the trays. In order to conveniently accommodate the spools and to line them up so that similar spools are in the same row, each tray is equipped with inverted T-shaped thread supporting members 70 and 71 shown in section in Fig. 10. These T-shaped members 70 and 71 are arranged with the horizontal portion 72 thereof near the lower part of the tray and the vertical partition portions 73 extending upwardly. The end of each vertical portion 73 is equipped with a projecting pin 74. These pins are designed to engage in a comb-like positioning member shown at 75. Each tray has two of these comb-like positioning members, one on the front wall 65 and one

on the rear wall 66. The pins 74 of the T-shaped partitions are designed to engage in the teeth of this comb-like member to permit the T-shaped member to be positioned in any desired location across the width of the tray. The T-shaped members are first spaced as desired and then the comb-like members are slid down to engage the pins and lock all the members in place. Normally these T-shaped partitions are positioned so that spools of thread of various lengths and diameters can be conveniently arranged on and between them. Such spools are shown in dotted lines at 76.

Some or all of the drawers may be equipped with partitions such as those shown in Figs. 3 and 7. These partitions consist of a series of relatively tall partition members running from the front to the rear of the drawer. These are shown at 80, 81, 82, 83 and 84 (Fig. 7). Each of these is equipped with a series of vertical slots in the lower portion thereof so as to give it the appearance of a coarse comb. Each partition member 80, 81, 82, 83 and 84 is like each other in regard to the height, the proportions and the position of the slots. Running crosswise of the drawer and about half as high as the partition members 80, 81, 82, 83 and 84 are partition members 85, 86, 87, 88, 89, 90 and 91 which pass through the slots in the taller partition members and are disposed at right angles to the taller members. The result is that the drawer is divided into a series of small square compartments. With this type of partition arrangement of course some variations may be made in the size and arrangement of the compartments.

The space where a single drawer would normally be positioned has a shelf 93 thereon (Fig. 1). Other spaces shown occupied by drawers may be similarly treated if it is desired to have shelf space under the upper display portion of the cabinets instead of drawers.

Section C is a unit very much like section A. It is shown made up of a lower portion 94 and an upper display portion 95. The lower portion is constructed like section A. The upper portion has the general shape and configuration of one of the tray compartments except that it is not equipped to receive trays but is equipped with a front retaining board 96. This compartment is designed to receive general items and may or may not be equipped with partitions.

Section D is very much like section B. It is shown with six drawers 100, 101, 102, 103, 104, 105. These are identical in construction with the drawers 10, 11, 12, 13 and 14 and therefore they will not be described again. The upper display portion of the section D shown at 106 is made in one large piece designed to rest upon the drawer retaining portion of this section D. The general shape of this display section as seen from the side is the same as the display section for the spools of thread and display section 95 on the top of section C. This section has partitions in it as shown in Figs. 4, 12 and 13. Section 105 has two side or end panels 107 and 108, a back panel 109 and a narrow front panel 110. The container for the articles to be displayed has a bottom portion 111 and an upper side 112. Over this display portion is the panel 113 for receiving the names, prices or the like. This is similar to the upper display panel shown in more detail in Fig. 9. The partitions in this display portion consist of partition members running from the back toward the front of the display

drawers others running lengthwise thereof. Alternate partition members have slots cut there-in at right angles to the longitudinal axis there-of, some from the top down about half way and the adjacent one from the bottom up about half way. These front to back partition members are shown at 115 and 116. The partition members which run across the display box or drawer are shown at 117 and 118 and are the same except one is longer than the other (Fig. 12). As shown in Fig. 14 these transverse partition members have notches or rabbets cut from the ends there-of. As viewed in Fig. 14 it will be seen that the nearer end has the notch or rabbet cut out of the lower portion and the corresponding notch or rabbet from the upper portion of the far end of the partition. This permits these partitions to cooperate with the longitudinal partitions wherein the notches are arranged alternately on the lower portion or the upper portion of adjacent partitions. This arrangement of the partitions provides considerable flexibility in regard to size and location of the compartments and of course all the partitions may be readily removed if it is desirable to show large articles.

The drawers in compartment D are furnished with a slightly different form of partition than those in compartment B. In compartment D the partitions running from the front to the back of each drawer are about half as high as the drawers are deep. They are shown at 120 (Fig. 4). The transverse partitions are shown at 121. The partitions 120 of which there are only two shown (see Fig. 8) are equipped with notches on the top thereof which go down about half way. The transverse crosswise partitions 121 are equipped with notches on the lower portions thereof. Both partitions are of the same height and they cooperate to divide the drawer up into sections such as squares or rectangles.

The device described is capable of considerable manipulation first, because it is made up of four different sections which may be separated and set up independently. The drawers may be all used, or some used, or none used. The open display boxes on the top of the device may be readily removed leaving a flat top which can be converted into a table or counter. Because the drawers are movable toward the front or back of the cabinet they are convenient for use by a sales person who might find himself or herself on either side of the cabinet when in need of something inside the drawers.

In the light of the foregoing description the following is claimed:

In a display cabinet of the character described, a display section comprising a pair of end panels, a back panel and bottom and having an open top and an open front, a set of spaced grooves in

each end panel sloping downwardly from the back of the section to the front, the grooves in one end panel being alined with the grooves in the other end panel to form pairs of alined grooves, openings in the back panel extending from end to end thereof each of which is alined with a pair of alined end panel grooves, a tray disposed in and between each pair of alined grooves and movable through the corresponding opening in the back panel, said trays being spaced one above each other and each being shorter than the one beneath it, each tray having means on its forward side for receiving identifying indicia, a plurality of tracks in each tray for supporting thread spools and like articles thereon, each track extending from the back to the front of the tray and being movable width-wise thereof, pins in the ends of each track, a transverse comb-like member disposed at the front and back of each tray for engaging the pins to retain said track in position on the tray, an overhang extending over the rear portion of the display section, and means on the overhang for receiving identifying matter characterizing the articles in said trays.
